DESCRIPTION

U.S. PATENT DOCUMENTS

FIG. 1 is a right perspective view of the electronics interface housing for luggage.

8,113,855 B2 * 2/2012 Green H01R 13/6675 439/131
D849,996 S * 5/2019 Duque D27/194

FIG. 2 is a left perspective view thereof;

FIG. 3 is left side view thereof;

FIG. 4 is a front view thereof;

FIG. 5 is a right-side view thereof;

FIG. 6 is a rear view thereof;

FIG. 7 is a top view thereof;

FIG. 8 is a bottom view thereof;

FIG. 9 is a right perspective view thereof shown in a position of use within a piece of luggage; and,

FIG. 10 is a right-side view thereof shown in a position of use within a piece of luggage.

In all figures, broken lines illustrate environmental structures and form no part of the claimed design.
